UNITED STATES PATENT OFFICE.

PETER GERING, OF BURTON, KANSAS.

WIND-ENGINE.

SPECIFICATION forming part of Letters Patent No. 254,303, dated February 28, 1882.

Application filed December 9, 1881. (No model.)

To all whom it may concern:

Be it known that I, PETER GERING, a citizen of Burton, Kansas, residing at Burton, in the county of Harvey and State of Kansas, have invented certain new and useful Improvements in Wind-Engines; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to wind-wheels and their connections to water-elevating apparatus; and the novelty consists in the construction and arrangement of parts, as will be more fully hereinafter set forth, and specifically pointed out in the claim.

One of the objects of the invention is to accommodate the wheel to greater and lesser velocities of wind by such an arrangement that the lesser velocity will have a more direct action upon the wheel than the greater, and thus avoid the wrenching and friction of the wheel-shaft in its bearings. It being well known that the upper portion of the wheel receives the wind of the greater velocity, I incline my wheel from a vertical plane in such a manner that the lower sails will be farther from the shaft-bearings than the upper ones; and by this arrangement the lower portion receives the direct action of the wind, which, being deflected by the incline of the plane of the wheel, creates a current in that direction and materially affects the force of the wind upon the upper portion. This arrangement equalizes the force of the wind upon the wheel and tends to make an equilibrium when the proper incline is attained.

Other objects and advantages will be obvious from the construction, which will be described and illustrated.

In the accompanying drawings, Figure 1 is a rear elevation of my improved windmill. Fig. 2 is a side elevation thereof; and Figs. 3 and 4 are detail views of elevating-buckets, &c.

In carrying out my invention I use a frame-work or tower, A, of suitable construction, shown in the present instance mounted upon

the walls of a flume or "pan," B, within which are arranged buckets a, secured to an endless chain, a', to elevate water into a dam for motive power. The pan or flume B has a chute or forwardly-inclined portion, b, to readily return the drippings or undischarged water of the buckets to the pan or flume. This arrangement of parts will be referred to hereinafter more fully.

C is a turn-table or support mounted to revolve upon the tower A to permit the shifting of the wheel with the change in the direction of the wind, as is common.

D is the wheel, whose hub e has a number of 65 vanes or sails, D', and whose shaft D² is journaled in boxes secured in or upon the cross-pieces at the upper end of the turn-table or support C. The vanes or sails D' may be connected together by chains or other suitable 70 means, d, and also to a projecting portion of the shaft D similarly. It will be noticed that the wheel, with its shaft, is disposed in an oblique or inclined position to cause its lower part to extend beyond and its upper part inward from 75 a vertical plane passing centrally through it, enabling its lower part to receive the direct force of the wind of lesser velocity and thus counterbalance the loss of force upon the upper part, where the wind of greater velocity is deflected by the current passing across the face 80 of the wheel in the direction of the incline. The turn-table supporting the wheel-shaft has a vane, E, to aid the shifting thereof by the wind.

Upon the shaft D² is a large pinion, e, which communicates the motion thereof to a pinion, f, on a vertical shaft, F, bearing in the tower or frame-work A, and having at its lower end a pinion, g, gearing with a second pinion, h, 90 on a driving shaft, h', suitably journaled in the tower at its base. The shaft h' has also a driving-belt pulley, h², for transmitting motion by belt or otherwise to the mechanism or device to be operated.

G is a lever pivoted at one end to the side of the upper end of the turn-table C, and having a strap of metal, i, or other suitable material connected to it, and passing over the periphery of the driving pinion e, with its other end secured to the opposite side of the turn-table. The free end of the lever G has an at-

tached spring, e' , the inherent force of which is designed to hold the strap i off the pinion e , except when it is desired to retard or stop the wheel, in which case the force of the spring 5 is overcome by the operator through a cord, m , to depress the lever G , and the strap i is forced into frictional contact with said pinion.

To again refer to the endless chain of buckets, it will be noticed that its shafts j are suitably hung in the flume or pan walls and have 10 sprocket-wheels k , which engage with the chain-belts a' to effect the movement of the buckets a .

The chain-belts may be made of twisted links or of links made in either of the forms shown 15 in Figs. 1 and 4. One of the shafts j has a pulley, around which is passed a belt, l , for driving it and operating the chain of buckets by the windmill.

Instead of constructing the endless chain of buckets as above described, the same end may be attained as shown in Fig. 3, where the buckets are connected together by links m and provided with friction wheels or disks m' , two at 20 each end of each bucket, traveling upon rails n , and the shafts j , provided with large disk-wheels K , having peripheral notches engaging 25 with the short axes of the disks m' .

From the foregoing it will be seen that different forms of sprocket-wheels, as well as different forms of chain-belts, can be used for the 30 endless chain of buckets.

It will be further noticed that the tower or frame-work A , with its superposed machinery and inclosed gearing and shafts, can be transported from place to place for elevating water 35 from a well and for other similar purposes, in addition to that shown and particularly described.

The specific construction of the elevating mechanism is designed to be the subject-matter 40 of a separate application.

I am aware that it is not broadly new to incline wind-wheels for other purposes.

What I claim as new is—

The shaft D^2 and pinion e , combined with 45 strap i , lever G , spring e' , and an operating-cord, m , as and for the purposes specified.

In testimony whereof I affix my signature in presence of two witnesses.

PETER GERING.
